CHOKER HOOK

William A. Meighan, Oswego, Oreg.

Original application April 19, 1948, Serial No. 21,825. Divided and this application May 16, 1951, Serial No. 226,639

9 Claims. (Cl. 294—75)

1

This invention relates to a choker hook for use with a wire choker rope in detachably but positively holding a bundle of logs, pulp wood lengths, pieces of cord wood, and the like while such bundle is in transit. More particularly, this invention is a division of my copending application Serial No. 21,825, filed April 19, 1948, and entitled Bundling Choker.

In the logging industry, where my invention is most widely used, choker ropes are used to drag logs or felled trees from the forest to a waterway or other convenient site from which the logs are transported to the mill. These ropes are necessarily large in diameter and are usually constructed of a number of wires woven into the form of a heavy cable to provide adequate strength. Accordingly, they are very stiff and resist bending. This stiffness results in considerable difficulty being experienced in the formation of knots or other attaching manipulations such as the attachment of terminal fittings and choker hooks. Heretofore, the difficulty has been overcome or avoided by attaching closed loops or ferrules to the end of the wire rope with a clamp, solder, babbitt, or the like. Such loops or ferrules serve as means for attaching the end of the rope to a hook or other device slidably mounted on the rope. It has been my experience that this procedure and this attachment structure necessitate the use of special equipment which must be available at the logging site. On the other hand, even though these fastening means are provided, they do not afford a positive grip for securing and holding a bundle of logs or lengths of pulp wood. Instead, these fastening means are limited in their use to the hauling of one log or timber at a time.

The limited usefulness of the present-day fastening means is a disadvantage which is amplified by modern logging operations. Thus, the sharp decline in the quantity of available timber has made necessary the salvage of cord wood, pulp logs, second-growth timber and water-soaked lengths. These secondary or short length wood pieces are of use in the manufacture of paper pulp, cardboard pulp, wallboard, and other commodities made from ground or defibered woods. Economic and profit factors, however, prohibit handling of such wood in individual pieces, and the choker ropes heretofore employed are incapable of positively securing and maintaining a bundle of such wood pieces in compact form during the logging and freighting operations. This is because the choker ropes maintain a relatively firm hold on the logs only while sufficient tension is maintained upon the

2

drag line secured to the choker loop. Also, when a bundle of logs is being dragged over the ground, any relaxation in the tension of the line immediately loosens the grip of the choker and some of the logs may slip away from the bundle or the entire bundle may become disarranged. Moreover, the hold on the bundle of logs is relaxed when the drag line is removed even if a bundle is successfully hauled from the forest and loaded upon freight cars, logging trucks, or a waterway.

Having in mind the above outlined disadvantages, it is a principal object of my invention to provide a choker hook which will grip both the end and an intermediate portion of a rope in such a manner that the gripping hold will not be relaxed except after a positive manual manipulation thereof.

Another important object of my invention is to provide cooperating jaws for a choker hook, which jaws are arranged to receive an intermediate section of the choker rope and to resist movement of said rope in the direction producing increase in the size of the choker loop until and unless positive disengagement is effected.

A further object of my invention is to provide a choker hook in which release of an intermediate section of the rope is accomplished by the conscious manual movement of a stepped pin having different effective diameters.

Other objects and advantages of my present invention will be hereinafter described with reference to the following detailed description, taken in connection with the accompanying drawings, in which:

Fig. 1 is a front view of a choker hook embodying the features of the instant invention and showing a wire rope engaged at one end in the rope coupling means thereof and, at an intermediate portion, between the saddle and shoe thereof; and

Fig. 2 is a fragmentary side view of the choker hook of Fig. 1, indicating, by dashed lines, the position to which one of the links may be pivoted to relax the grip of the saddle upon the intermediate portion of a wire rope.

In Fig. 1 of the drawings, I have shown an elongated body member 1 having rope coupling means 2 at one end thereof and a gripping shoe 3 at the other end thereof. The rope coupling means 2 includes an offset member 4 provided with a centrally arranged eye 5. In addition, a pair of axially aligned tunnels 6 and an aperture 7 are formed intermediate the ends of said body member. Preferably, this entire structure is cast from iron or steel to provide a strength com-

mensurate with the use of the choker hook in a logging operation.

To secure a rope such as the illustrated cable 8 to the coupling means 2, one end of said rope first is threaded through the eye 5. Thereafter, this end of the rope is threaded rearwardly through the aperture 7 and is flexed upwardly behind itself to lie in a lateral plane across the tops of the aligned tunnel 6 as shown in Fig. 1. The rope is then bent back upon itself and threaded through the aligned tunnels 6. This type of knot and the procedure for forming it is more fully described in my United States Patent No. 2,240,510, issued May 6, 1941, and entitled Logging Choker and Fittings Therefor. It is to be noted, however, that any rope coupling means of conventional type may be utilized in place of that illustrated at 2 since the details of the present invention do not depend for novelty upon the manner in which the end of the rope is secured to the choker hook.

Referring more particularly to the inventive details of the choker hook, I have shown a first pivot means or pivot lug 9 and a second pivot means or bearing flange 10 carried on the opposite sides of said body member 1. Above the pivot lug 9 and to either side thereof are spaced flanges 11a and 11b also projecting from the side of the body member 1. As shown in Fig. 1, the left flange 11a is provided with an elongated slot 12 and the right flange 11b is provided with a reduced slot 13. Slidable laterally within these slots 12 and 13, I have shown a stepped pin 14 having an enlarged end 15 and a reduced end 16. Each end of the pin 14 is provided with a shoulder stop 17 and the reduced end 16 is drilled as at 18. The drilled hole 18 accommodates a piece of wire or a cotter key 19 to define a removable keeper member for locking the pin 14 against movement.

As best shown in Fig. 2, I have provided a U-shaped grip member 20 having two legs or link members 21 and 22 joined by a saddle portion 23. The saddle portion 23 is joined, at the ends thereof, to the two links 21 and 22 by the pivot connections 24. In addition, the right link 21 (see Fig. 2) is mounted pivotally on the bearing flange 10, as at 25, and the left link 22 overrides the pivot lug 9 similarly to articulate this left link. Thus, the links 21 and 22 and the saddle portion 23 are carried for pivotal movement about the lateral axis X (see Fig. 2) between an open position in which the saddle 23 is spaced from the shoe 3 and a rope grip position in which the saddle 23 closely overlies the shoe 3.

Turning now to the stepped pin 14, two operative positions therefor have been shown in Fig. 1. In the full line position, the enlarged end 15 straddles and overlies the top portion of the left link 22 to hold this link against the lateral movement yet to permit the aforementioned pivotal movement about the lateral axis X. In the dashed line position of Fig. 1, the reduced end 16 overlies the left link 22 to release this link for pivotal movement about the lateral axis Y to the dashed line position of Fig. 2. Thus, the wire 19 serves as a keeper member to prevent inadvertant or premature displacement of the pin 14.

In operation, the end of the choker rope 8 is secured to the choker hook, as by the rope coupling means 2, and the rope is looped about a bundle of logs or lengths of cord or pulp wood. With the stepped pin 14 in the locked position and the wire keeper 19 affixed as shown in Fig. 1, the saddle 23 is rotated about the lateral axis X away from the gripping shoe 3 sufficiently to thread the rope end through the space thus defined to

introduce an intermediate section of the rope 8 into the saddle. The free end of the rope is then secured to a drag line or a come-along in conventional manner. As the drag line exerts a pull upon the rope 8 in the direction of the arrow 26, the diameter of the rope loop encompassing the bundle of logs thereby is decreased.

As the pull on the drag line continues, the articles are brought into a compact bundle and further closing of the choker rope loop is prevented. At this time, the pressure exerted by the drag line upon the rope 8 pivots the saddle 23 and the links 21 and 22 about the lateral axis X into the rope gripping position shown in Fig. 1. Thus, the intermediate portion of the rope 8 frictionally is gripped between the saddle 23 and the shoe 3 to retain the bundle of logs in compact form. Moreover, by providing a sharply curved receiving end 21 upon the saddle 23, a sharp, but not a shearing, bend in the rope is formed. This sharp bend greatly increases the holding power of the clamp and prevents the bundle from coming loose. In fact, the more tightly the logs are bundled, the tighter my choker hook will hold them even after the drag line is backed off or is released.

If the bundle thus secured is logs, it thereafter will be hauled from the forest to a shipping site and the tension of the drag line will be released. At this point, it should be apparent that no tension need be maintained upon the free end of the choker rope since the outward pressure of the bundle maintains the clamp in positive gripping position. The bundle thus formed may be loaded upon a truck or freight car, or it may be discharged into a waterway for transport to the mill for processing.

At the mill or when it is desired to release the bundle, the keeper wire 19 is removed from the drilled hole 18 in the reduced end of the pin. Thereafter, a workman applies a sharp blow with a hammer upon the small shouldered end of the pin at 17. This blow drives the pin from the full line the dashed line position shown in Fig. 1. Almost instantaneously, the left link 22 is released for pivotal movement about the lateral axis Y and the saddle 23 will spring away from the rope 8 to release the same. The choker hook is then withdrawn from about the bundle and returned to the logging site for further use.

It will now be seen that I have served my inventive objects by providing a choker hook in which the saddle portion thereof is mounted for selective pivotal movement about a lateral axis between two different positions. In the first such position, the saddle is in close proximity to the shoe to define a rope gripping position therewith. In the second such position, the saddle is spaced from the shoe out of rope gripping relationship therewith. Additionally, I have provided a stepped pin which is movable laterally to release one of the links for pivotal movement about a second lateral axis perpendicular to the first lateral axis. This second pivotal movement frees the saddle and choker rope. Thus, my choker hook is easily released when desired yet a positive, conscious effort is required to effect such a release.

I claim:

1. A choker hook, comprising an elongated body having rope coupling means at one end thereof, a saddle means joined pivotally to said body intermediate the ends of the latter, and a cam-shaped shoe fixed to the other end of said body, said shoe lying within said saddle and

cooperating therewith to engage a rope in one operative position, said saddle being pivotable selectively about an axis to two different positions in one of which it is in close proximity to said shoe in a rope gripping relationship therewith and in the other of which it is spaced from said shoe out of rope gripping relationship therewith, a movable pin means carried by and extending laterally of said body to define a portion of the pivotal joining connection between said body and saddle, said pin means being movable independently of said saddle pivotal movements to relax said rope gripping relationship, said saddle means including a pair of articulated links one of which is joined pivotally to each side of said body, said pin means overlying one end of one of said links when said saddle defines said rope gripping relationship and being spaced from said one end when said rope gripping relationship is relaxed.

2. A choker hook, comprising an elongated body member carrying coupling means at one end and a gripping shoe at the other end, a U-shaped grip member having two leg portions joined by a saddle portion arranged selectively to overlie said shoe, pivot means carried on opposite sides of said body and defining a first lateral pivot axis, each said leg portion being joined to one of said pivot means, said saddle portion thereby being carried for pivotal movement about said first axis between an open position spaced from said shoe and a grip position closely overlying said shoe, and movable pin means operatively carried by said body member and bearing on one of said leg portions selectively to release said grip member for pivotal movement about a second lateral pivot axis perpendicular to said first lateral pivot axis.

3. A choker hook, comprising an elongated body member carrying coupling means at one end and a gripping shoe at the other end, a U-shaped grip member having two leg portions joined pivotally by a saddle portion arranged selectively to overlie said shoe, first and second pivot means aligned on opposite sides of said body intermediate the ends thereof to define a first lateral pivot axis, each said leg portion being joined to one of said pivot means, said saddle portion being carried for pivotal movement about said first axis between an open position spaced from said shoe and a grip position closely overlying said shoe, and movable pin means operatively carried by said body member for movement relative thereto and bearing on one of said leg portions selectively to release said grip member for pivotal movement about a second lateral pivot axis perpendicular to said first lateral pivot axis, said pin means including a stepped pin movable from a position astraddle said one leg portion to a release position out of contact with said leg portion.

4. A choker hook, comprising an elongated body member carrying rope coupling means at one end for securing the end of a rope thereto, a rope gripping shoe carried adjacent the other end of said body member, a U-shaped grip member having a saddle joined pivotally to said body for cooperation with said shoe, said grip member being mounted for pivotal movement about a lateral pivot axis between two positions, said saddle being spaced from said shoe in one position and closely overlying said shoe in a second position to grip an intermediate portion of said rope between said shoe and saddle, and movable means operatively carried by said body member and releasably bearing on said grip member to relax said saddle from said second position and

release said intermediate rope portion, said latter means including a stepped pin movable laterally in a direction perpendicular to said lateral pivot axis.

5. A choker hook, comprising an elongated body member carrying rope coupling means at one end thereof for securing the end of a rope thereto, a rope gripping shoe carried adjacent the other end of said body member, a U-shaped grip member joined pivotally to said body and having two leg portions joined by a saddle portion, said grip member being mounted for pivotal movement about a lateral pivot axis between two positions in cooperation with said shoe, said saddle being spaced laterally from said shoe in one position and being closely adjacent said shoe in a second position to grip an intermediate portion of said rope between said shoe and saddle, and movable pin means operatively carried by said body member

20 for movement relative thereto and releasable bearing on one of said leg portions to relax said saddle from said second position and release said intermediate rope portion, said pin means including a stepped pin movable laterally in a direction perpendicular to said lateral pivot axis in response to a conscious manual blow thereupon.

6. A choker hook, comprising an elongated body having coupling means at one end and a gripping shoe at the other end, a pair of link means disposed one on each side of said body and mounted for pivotal movement about a common lateral axis, a saddle member companion to said shoe and carried by said links for pivotal movement therewith between an open position spaced from said shoe and a grip position closely adjacent thereto, and movable means operatively carried by said elongated body for releasing one of said links for pivotal movement about a second lateral axis perpendicular to said common lateral axis.

7. A choker hook, comprising an elongated body having rope coupling means at one end and a rope gripping shoe at the other end, a pair of link means disposed one on each side of said other end of said body and mounted for pivotal movement about a common lateral axis, a saddle member companion to said shoe and carried by said links for pivotal movement therewith between an open position spaced from said shoe and a rope grip position closely adjacent thereto, and movable pin means operatively carried by said body for movement relative thereto and to release one of said links for pivotal movement about a second lateral axis perpendicular to said common lateral axis, said pin means including a removable keeper selectively for locking said pin against movement.

8. A choker hook comprising, in combination, an elongated body, a choker rope coupling means angularly disposed on one end of said body, rope gripping shoe means on the opposite end of said body, a saddle member companion to said shoe for slidably receiving an intermediate section of choker rope, means pivotally securing one end of said saddle member to one side of said body, a pivot lug projecting from the opposite side of said body, a link member pivotally secured at one end to the opposite end of said saddle member and releasably mounted at its opposite end 60 on said pivot lug, spaced flanges projecting from said body adjacent the sides of said pivot lug, a stepped pin having a plurality of effective diameters throughout its length, and transverse slots in said flanges having different effective diameters for slidably receiving said pin, the enlarged

portion of said pin being arranged to overlie the link on said pivot lug to define a locking position and to disengage said link to define a retracted position, the intermediate portion of said saddle member being disposed in opposing relation to said shoe and cooperating therewith to secure releasably said choker rope therebetween.

9. A choker assembly comprising, a choker rope having a terminal fitting on one end thereof and a choker hook on the opposite end thereof, said choker hook comprising, in combination, an elongated body, rope gripping shoe means on one end of said body, a saddle member companion to said shoe for slidably receiving an intermediate section of said choker rope, link means pivotally securing one end of said saddle member to one side of said body, said link means including a first link pivotally secured at one side to said body, a pivot lug projecting from the opposite side of said body, a second link pivotally secured at one end to the opposite end of said saddle member and releasably mounted at its opposite end on said pivot lug, two spaced flanges projecting from said body adjacent the sides of said pivot lug, a pin having an enlarged end and a reduced end,

15 an elongated slot in one of said flanges and a reduced slot in the other of said flanges for slidably receiving said pin, removable keeper means in the reduced end of said pin for retaining the latter in locking position, shoulder stop means on the reduced end of said pin for retaining said pin in said flanges, the enlarged end of said pin being arranged to overlie said second link to define a locking position and to disengage said second link to define a retracted position, the intermediate portion of said saddle member being disposed in opposing relation to said rope gripping shoe and cooperating therewith to releasably secure said choker rope therebetween.
